KNITTING MACHINE

Albert Friedmann, Wyomissing, Pa., assignor to
 Louis Hirsch Textile Machines, Inc., New York,
 N. Y., a corporation of New York

Original application December 11, 1933, Serial No.
 701,737. Divided and this application November
 15, 1934, Serial No. 753,201

15 Claims. (Cl. 66—127)

This invention covers a new and useful improvement in stockings, a method of producing them, and a machine by which the method may be performed.

5 The subject matter of this application has been divided out of a copending application filed by me on December 11, 1933, bearing Serial No. 701,737.

In the knitting of silk hosiery of fine quality, 10 those skilled in the art have considered it necessary to use not only the same gauge and quality of thread but the same identical thread for the knitting of the parts of the stocking which are most conspicuous, such as the leg and instep.

15 It was thought that only in this way could the most uniform fabric be produced. However, in spite of the greatest care in manufacturing the thread the diameter of one part frequently differs from that of another. The result is that in 20 the knitted fabric the courses knit from the heavier part of the thread lie adjacent each other so that rings or bands appear in the fabric which are very noticeable and greatly mar the appearance of the stocking. So long as a single thread

25 is used the knitter can do little to alter the situation. However, by knitting succeeding courses of the same kind of thread but from different cones the courses knit from each of them may be separated by other courses of the other

30 threads, the irregularities in the thread then becoming less apparent. The so-called "ringless" stocking is the result of this practice which is becoming increasingly popular with hosiery manufacturers. It is knit of three separate threads laid successively in adjacent courses so that the 35 same thread appears only in every third course. However, the method heretofore employed has not been altogether satisfactory. Three main thread carriers are required, two of which are

40 idle and released from the control of their frictions while the other is working. When the working carrier starts there is danger that it will drag across one of the idle carriers displacing it from its correct position over a certain one of the selavage dividers. When the working carrier

45 rod strikes a stop at the end of a stroke it sometimes jars an idle carrier out of position. Either happening is likely to cause needle breakage and press offs with consequent reduced output.

50 Hence the machines are generally operated at lower speed than otherwise necessary and carrier rod arresting devices are employed which further complicate an already complicated machine.

55 Furthermore, when accepted practice is fol-

lowed it is difficult to obtain a good selavage for the reason that between the end of one course knit with a thread and the beginning of the next course knit with the same thread there is a loose length of the thread lying across the two intervening courses. Sometimes this is caught up in the intervening courses in which case it is a matter of chance whether trouble results. Ordinarily it is not caught up but hangs loosely along the selavage where it may be cut easily or cause 10 needle breakage. It also makes neat seaming difficult.

By the invention of this application although three carriers are used to lay three separate threads in successive courses, a ringless fabric is 15 produced in which there are no loose selavage threads. To the contrary, each thread is knit into each course, and all three thread carriers are constantly working under control of their respective frictions. No thread carriers are ever 20 floating free so that the danger of displacement by jar or contact with moving thread carriers is eliminated without the use of arresting devices. Therefore, the machine may be operated at the highest practicable speed. As to the fabric, it is 25 "ringless" and its selavage is straight, firm, and uniform and is reenforced to any width desired.

Another advantage derived from this invention is that a "triple heel" or "heel within heel" 30 may be knit with five carriers instead of the customary minimum of seven freeing two carriers for other uses. Since full fashioned hosiery machines are usually equipped with only seven carriers this is a decided improvement. A novel means of driving the three thread carriers in the 35 desired way is also included in this invention, the nature of which will be made clear by the following description and drawings, of which

Figure 1 illustrates diagrammatically the manner in which the threads are laid by the thread carriers involved in each of a series of consecutive courses;

Figure 2 diagrammatically illustrates the changing positions of the carrier rods involved in laying the courses shown in Fig. 1;

Figure 3 is a diagrammatic view of a series of courses showing the positions of the three threads in each as viewed from the back of the machine looking towards the front;

Figure 3—A is a diagrammatic view of a series of courses of ringless fabric knit in the conventional manner viewed as in Fig. 3;

Figure 4 is a diagrammatic illustration of one type of stocking embodying the invention;

Fig. 5 is a plan view of the knitting machine of this invention;

Fig. 6 is a sectional view of the machine of Fig. 5 along the line 6—6 in the direction of the 5 arrows;

Fig. 7 is a sectional view of the machine of Fig. 5 along the line 7—7 looking in the direction of the arrows; and

Fig. 8 is a front elevation of a portion of the 10 machine of Fig. 5.

The stocking of this invention is not limited to any particular type but may be any of the types which can be knit upon a flat knitting machine. Figure 4, for example, is intended to illustrate 15 diagrammatically a full fashioned stocking leg with a triple heel since this type well illustrates the versatility of the invention. The noticeable difference between this stocking and other ringless stockings is the reenforced selvage which 20 may be extremely narrow if desired, so that it disappears in the seam, or may be made as much wider as desired without affecting the general 25 method of knitting.

As already stated the present practice in knitting ringless stockings is to use three threads 25 laid in rotation in successive courses, the thread used for one course being simply carried down across the ends of the two following courses and then employed for the next course, that part of 30 the thread between the end of the first course and the beginning of the next course in which it is used lying loose. Each thread is laid the full width of the fabric. If reenforced selvages are desired by this method two additional thread 35 carriers are required, one for each selvage or a total of five thread carriers.

By the method of this invention all of three 40 thread carriers work simultaneously upon the same courses, one laying the thread across the entire width of the fabric and the other two laying reenforcing threads for the two selvages. Fig. 1 illustrates diagrammatically the threads 45 as they are laid in each of six consecutive courses. When as shown in diagram A of Fig. 1 thread 1 is laid the full width of the stocking from left to right thread 2 will be laid also from left to right and also in the same course but only the width of the right selvage. Simultaneously 50 thread 3 will be laid from left to right but only across the left selvage. When this course is knit it will produce a fabric with a reenforced selvage on each edge and all three threads will be contained therein.

Diagram B of Fig. 1 represents the first course 55 as described above, and also the second course. In this second course the thread carriers have traveled, of course, in the reverse direction from right to left. Thread 1 which during the first course was laid across the full width of the stocking has now in the second course been laid from right to left across the right selvage as shown at 4. Thread 2 which in the first course was laid from left to right across the right selvage has now been laid from right to left across the full 60 width of the fabric as shown at 5, and thread number 3 which in the first course was laid from left to right across the left selvage has now been laid from right to left across that same selvage again as shown at 6. Thus when this course is 65 knit a second course has been completed having the same characteristics as the first, all three threads having been incorporated.

The laying of the threads for the next course 70 is illustrated by diagram C of Fig. 1. In this 75 the first thread is laid back across the right

selvage from left to right as shown at 7. The second thread is laid across the left selvage also from left to right as shown at 8, and the third thread is laid across the entire width of the fabric from left to right as shown at 9.

In the following course (diagram D of Fig. 1) 5 the threads are laid as follows: Thread 1 which in the first course was laid across the full width of the stocking in the second course across the right selvage in one direction and in the third course across the same selvage in the other direction now is again laid across the full width of the stocking in the opposite direction, namely, from right to left as shown at 10. Thread 2 which in the first course was laid across the 10 right selvage, in the second course across the full width of the stocking, and in the third course across the left selvage is now laid across the left selvage again but in the opposite direction, from right to left, as shown at 11. Thread 3 which 15 in the first course was laid across the left selvage from left to right, in the second course across the left selvage again from right to left, and in the third course across the full width of the 20 fabric from left to right is now laid from right to left across the right selvage as shown at 12, completing the laying of the three threads for a 25 course identical with the others.

The laying of the next course is shown in 30 diagram E of Fig. 1. In this thread 1 is laid from left to right across the left selvage as shown at 13. Thread 2 is laid across the entire width of 35 the fabric from left to right as shown at 14, and thread 3 is laid across the right selvage from left to right as shown at 15.

The laying of the next course is shown in 40 diagram F of Fig. 1 as follows: Thread 1 is laid across the left selvage again but in the opposite direction from right to left as shown at 17; thread 2 is laid across the right selvage from right to left as shown at 18; and thread 3 is laid across the full width of the fabric from right to left as shown at 19 completing the laying 45 of the three threads for another course similar to the preceding courses.

In the following course, as shown in diagram 50 G of Fig. 1 thread 1 begins a new cycle by laying a thread from left to right the entire width of the fabric as shown at 20, as in the course first laid by it. Thread 2 will complete its cycle by 55 laying a course from left to right across the right selvage, as shown at 21. This places thread 2 in position to begin its next complete cycle by laying a thread completely across the fabric in the next course. Thread 3 which, it will be noted, is one step behind thread 2 in the cycle just as thread 2 was one step behind step 1, is laid in this course from left to right across the left selvage as shown at 22. Each thread passes through exactly the same cycle and is knit into 60 each course. All three carriers are working in the same direction during each course and are under control of their friction. There are no loose threads crossing other courses at the edges of the fabric although each thread in the body 65 of the fabric is separated from itself by two others to carry out the "ringless" idea. A firm, even, reenforced selvage is formed. The fabric may be narrowed as desired without interfering with the method of knitting, the narrowing being 70 performed in the usual way by the usual attachment.

The structure resulting from this method of knitting is diagrammatically illustrated by Fig. 3 which shows one selvage and a fragment of the 75

body of the fabric and how the three threads which are numbered 1, 2 and 3 (corresponding with Fig. 1) are incorporated in succeeding courses. Only two threads appear in each course 5 of the selvage of Fig. 3, the third thread being found, of course, in the other selvage which is not shown in the figure but which has the same loop arrangement.

To make the comparison between this fabric 10 and the conventional three thread ringless fabric perfectly plain the conventional fabric is shown in Fig. 3—A, in which the loose, or floating threads, on the selvage or edge of the fabric are clearly shown at 1^a, 2^a, and 3^a. Figs. 3 and 3—A 15 are based upon the assumption that the observer is viewing the fabric from the rear of the knitting machine looking towards the front. That is to say, in the order of knitting, the top courses shown in these figures precede the lower 20 courses.

Fig. 2 illustrates diagrammatically the three carrier rods 23, 24 and 25 in the positions which they assume for the laying of the threads as described in connection with Fig. 1. Each diagram 25 of Fig. 2 is lettered to correspond with the equivalent diagram of Fig. 1. The vertical lines 26 and 27 represent the usual end stops carried by the narrowing head. At the beginning of the laying of the course illustrated by diagram A in Fig. 1 30 the rods are in the position shown in position A—A, Fig. 2, rods 23 and 25 being at the extreme left, and rod 24 in the intermediate position which will bring its carrier over the inner or left edge of the right selvage. On the next stroke of the 35 friction rod all three rods will be driven to the right, as shown in position A of Fig. 2, carrier rod 23 being driven the full width, carrier rod 24 being driven to its extreme right position which will bring it across the right selvage, and carrier 40 rod 25 will be moved from its position on the extreme left to the right a distance corresponding to the width of the left selvage. As a result threads will be laid in this course as shown in diagram A, Fig. 1.

45 Upon the next stroke of the friction rod, which will be to the left, the carrier rods assume the positions shown in position B of Fig. 2, rod 23 being driven to the left a distance corresponding to the width of the right selvage, rod 24 also to 50 the left the full width of the fabric, and rod 25 to the left the width of the left selvage. This will lay the threads as shown in diagram B of Fig. 1.

On the next stroke of the carrier rods, which will be to the right, rod 23 will move to the right 55 across the right selvage, rod 24 will move to the right across the left selvage, and the third rod 25 will move to the right all the way across the fabric assuming the position shown in position C of Fig. 2 and laying thread according to diagram 60 C of Fig. 1. Upon the next stroke of the friction rod which will be to the left, as shown in Fig. 2 position D, rod 23 again moves across the full width of the fabric but to the left in the opposite direction to its last full stroke. Rod 24 returns 65 to the left across the left selvage again, and rod 25 moves to the left across the right selvage, the thread being laid as shown in diagram D. The following movements of the carrier rods shown in positions E, F and G of Fig. 2 will be under- 70 stood without detailed description. They result in the laying of threads in the three following courses as shown in the similarly numbered diagram E, F and G of Fig. 1.

75 It will be noted that during each stroke of the carrier rod operating mechanism first one rod

and then another moves across the full width of the fabric, and that the motion of the other two rods is limited to the selvages, one working on one selvage and the other working on the other. It will also be noted that at the end of each stroke 5 each rod is always in the correct position for the beginning of its next working stroke so that no idle courses are required and that all three rods are constantly under the control of their respective frictions.

10 In Fig. 4 is illustrated diagrammatically a stocking knit as described above, and having the socalled heel within a heel. That is to say, a heel having areas of single reenforcement in the upper parts of the heel tabs as shown at 28 and 29, the remainder of the tabs being overlaid by an additional reenforcement shown at 30 and 31. To form the single reenforcement of the heels between the lines A—A and B—B and also the intervening instep portion the same three thread carriers continue to function in the same way, the single reinforced areas being in effect wider selvages. For the forming of the double reenforcement areas 30 and 31 two extra thread carriers are required or five in all, instead of the 15 usual 7 which would be necessary if orthodox methods were followed. These extra threads are laid in the conventional manner back and forth across the heel tabs by the two extra thread carriers which are also operated in the conventional manner in properly timed relation to the other carriers operating upon the tabs. In view of the 20 fact that the constant demand of the industry is for more carriers than manufacturers can provide upon their machines, the release of two carriers 25 for other uses (which is tantamount to adding two more carriers to the machine) is of great value 30 and importance.

When the line B—B is reached where the 35 knitting of the instep portion is suspended, the 40 ringless method above described is discontinued and the remainder of the double reinforced heel tabs shown in Fig. 4 between the lines B—B and C—C are knit in the conventional way, three 45 thread carriers being employed for each tab.

The knitting of the foot may also be performed 50 in accordance with the above method and requires no further description. Obviously the method may be carried out upon a ledger and a footer, a single unit machine or, for that matter, manually. It results in a "ringless" stocking having 55 perfect selvages which may be of any width so as to be visible or not in the finished stocking, as desired. The difficulty resulting from free floating carrier rods and also from floating threads in the selvage is eliminated and perfect fabric is assured.

The method of knitting as described above may be performed, if desired, upon a flat knitting machine of generally standard design, the carrier rod 60 operating mechanism of which is modified somewhat as diagrammatically illustrated in Fig. 5. Carrier rods 23, 24 and 25 are shown. There are usually seven carrier rods on a standard flat knitting machine. The four other rods are omitted 65 from the drawings since they are standard in all respects and are operated in the conventional manner through friction rod 36 and frictions operated by the usual driving mechanism.

The three frictions 37, 38 and 39 which operate 70 carrier rods 23, 24 and 25 are of novel design. In so far as the friction features of these special frictions are concerned they are standard and consequently require no description. All of the 75 special frictions 37, 38 and 39 are essentially alike.

so that a description of friction 37 will suffice for all three of them. This consists of a friction box 42 equipped with the usual friction device (not shown) whereby it may be frictionally connected with friction rod 36 so as to be propelled thereby. Upon friction box 42 are pivotally mounted three fingers 43, 44 and 45, the length of finger 43 being such that it overlies carrier rod 23. Similarly finger 44 overlies carrier rod 24, and finger 45 overlies carrier rod 25. Behind, above, and parallel to the friction rod 36 a changing shaft 46 is rotatably mounted in suitable bearings supported by rod 91 parallel thereto. Shaft 46 is provided with one or more longitudinal spline slots 47 and upon it are three cams 48, 49 and 50. Each of these cams is slidable upon change shaft 46 and is provided with a spline key 51 (Fig. 6) engaging with spline slot 47 so that although they are slidable on shaft 46 they will, nevertheless, rotate when shaft 46 is turned.

Friction box 42 is provided with arms 52 and 53 through which changing shaft 46 passes. These arms are provided with bosses 54 at the point through which the changing shaft 46 passes 25 which rest against the outer sides of cams 48 and 50, to maintain the three cams 48, 49 and 50 in alignment with the rollers 56, 57 and 58 on the rear ends of fingers 43, 44 and 45 respectively, and to slide the cams on shaft 46 whenever friction box 42 moves, thus maintaining the cams in alignment with the rollers on the fingers at all times. Arms 52 and 53 also carry a cross rod 55 to which springs are attached which maintain the fingers in contact with the carrier rods except 30 when they are removed therefrom by the action of the cams. This will be described in detail in connection with another figure.

Also as will be fully described later, cams 48, 49 and 50 are so shaped and their respective working surfaces so distributed that when the forward end of any one finger is in its lowermost or operative position the other two will be rocked up into inoperative position. Rods 23, 24 and 25 are each provided with a double stop like that shown in Fig. 8 the space between the two stop surfaces 62 and 63 being sufficient to receive the end of a finger when it is in its down or operative position. Obviously when in this position any movement of friction 37 will be translated to a 50 rod through a finger.

The function of friction 37 is to propel the carrier rods 23, 24 and 25 the full width of the fabric, the term "full width" as used herein meaning from one edge to the other whether it 55 be the maximum width or some lesser width resulting from narrowing.

More specifically when rod 23 is to travel a distance equivalent to the full width of the fabric finger 43 will be swung down into engagement with stop 59 so that when friction 37 moves either to the right or left carrier rod 23 will be propelled in one direction or the other the distance permitted by end stops 40^a and 41^a. These end stops are the standard stops carried by the 60 narrowing heads.

Whenever carrier rod 24 is to be propelled the full width of the stocking, cam 49 will operate in a similar manner to permit finger 44 to engage with a similar double stop 60 on rod 24, and when carrier rod 25 is to be propelled the full width of the fabric cam 50 will operate to permit finger 45 to engage with a double stop 61 on carrier rod 25. The order in which these rods travel the entire width of the fabric has already been described. Therefore, the order in which fingers 75

43, 44 and 45 operate to drive them will also be evident.

Friction 38 is, as already stated, substantially identical to friction 37. It is provided with three fingers 64, 65 and 66 pivoted upon a friction box 5 67, the forward ends of the fingers overlying carrier rods 23, 24 and 25 respectively. The rear ends of these fingers are equipped with cam rollers 68, 69 and 70 which engage with cams 71, 72 and 73 slidably splined upon shaft 46 so that they will also rotate therewith. As in the case of friction box 37, friction box 67 is also provided with arms 74 and 75 enclosing the cams 71, 72 and 73 to guide these cams and maintain them in alignment with rollers 68, 69 and 70 whatever 15 the position or movement of friction 38 may be. The function of friction 38 is to move one or the other of carrier rods 23, 24 and 25 across one or the other of the selvages. Since it is to operate upon only one rod at a time cams 71, 72 and 73 20 are so designed and their working surfaces so positioned that they will maintain two fingers out of engagement with their rods while the remaining finger is engaged. The carrier rods 23, 24 and 25 are provided with another set of double 25 stops 77, 78 and 79 respectively, with which fingers 64, 65 and 66 may respectively engage to drive the rods. It will, therefore, be evident that friction box 38 may be used to select and operate any one of the three rods 23, 24 and 25 during 30 any knitting stroke, the rod selected being governed by the arrangement and design of the operating cams.

The third friction 39 is also of substantially identical construction to the other two. It is 35 provided with pivoted fingers 80, 81 and 82 the forward ends of which overlie carrier rods 23, 24 and 25 respectively. The rear ends of the fingers are also provided with cam rollers 83, 84 and 85 engaging with cams 86, 87 and 88 splined on shaft 46 so as to be not only slidable upon but rotatable therewith. The longitudinal position of these cams on change shaft 46 is under the control of friction box 39 through arms 89 and 90 which enclose the cams as described to maintain them 40 in alignment with rollers 83, 84 and 85 at all times. Carrier rods 23, 24 and 25 as shown, are provided with a third set of double stops 93, 94 and 95 with which fingers 80, 81 and 82 can engage to drive the rods. If desired the same set 50 of stops 77, 78 and 79 with which the fingers of friction 38 engage may be utilized for friction 39 provided the length of each of these frictions is small enough to permit them to be brought close enough together so that stops 77, 78 and 79 will 55 register with fingers 80, 81 and 82 on friction 39. Cams 86, 87 and 88 are also designed and their working surfaces positioned so as to maintain two of the fingers 80, 81 and 82 out of operative engagement with their carrier rods and to permit 60 one of the fingers to operatively engage.

The function of this friction 39 also is to drive one or the other of carrier rods 23, 24 and 25 across a selvage in one direction or the other. It will, therefore, now be evident that by means 65 of the fingers on the three frictions 37, 38 and 39 under the control of the nine associated cams the three carrier rods 23, 24 and 25 may be independently driven by friction rod 36 simply by causing one of the fingers on friction 37 to engage one rod, one of the fingers on friction 38 to engage another rod, and one of the fingers on friction 39 to engage the third rod during each knitting stroke. However, it is also evident that since friction rod 36 during each stroke recipro- 75

cates an unvarying distance all three frictions and consequently all three carrier rods would necessarily traverse the entire width of the stocking at each knitting stroke were not other means included to limit the stroke of two rods to the width of the selvages.

Reference to Fig. 2 will demonstrate that during each knitting stroke two rods move only the width of the selvage whereas the third rod travels the full width of the stocking.

To limit the inward travel of the carrier rods engaged in laying the heel tab threads use is made of the standard pointed heel attachment with several novel additions thereto. This attachment, as modified, is shown in the center of Fig. 5. It consists of a spindle 96 rotatably mounted in suitable bearings on brackets 97, 98 and 99 fixed to stationary shaft 91. Spindle 96 is divided into two oppositely threaded halves 100, 101. Internally threaded stop blocks 102 and 103 are mounted upon halves 100 and 101 respectively, of spindle 96 so that rotation of spindle 96 will cause blocks 102 and 103 to approach or recede from one another. To prevent rotation of stop blocks 102 and 103 around spindle 96 each stop block is also provided with a boss 103a slidably supported on shaft 91.

It will be evident that if carrier rods 23, 24 and 25 are provided with stops suitable to engage with stop blocks 102 and 103 the inward travel of these rods can be limited to less than their maximum and that this limited travel can be varied by racking blocks 102 and 103 outwardly or inwardly. However, it will be remembered that throughout the knitting of the stocking each carrier rod must not only work upon the selvages but at every third course must traverse the full width of the stocking. Therefore, an arrangement in which stops on the carrier rods must strike stop blocks 102 or 103 on every stroke will not be suitable. For this reason stop blocks 102 and 103 are so designed that the stops on carrier rods 23, 24 and 25 can pass under them. They are, however, each equipped with three adjustable stops, those on stop block 102 being numbered 104, 105 and 106 respectively, and respectively overlying carrier rods 23, 24 and 25. The stops on block 103 are numbered 107, 108 and 109 respectively, and also respectively overlie carrier rods 23, 24 and 25. As best shown in Fig. 7 each of these stops 104-109 is movable toward and away from its associated carrier rod. Carrier rod 23 is provided with additional stops 110 and 111 which will engage with stops 104 and 107 respectively, when these last mentioned stops are in their operative position. Carrier rod 24 is similarly provided with stops 112 and 113 engageable with stops 105 and 108 on stop blocks 102 and 103 and carrier rod 25 is also similarly provided with stops 114 and 115 engageable with stops 106-109 on stop blocks 102 and 103.

Whenever it is desired to limit the inward travel of any one of the three carrier rods in either direction this is done by moving the proper stops on stop blocks 102 and 103 down into operative position so as to engage with one or another of the stops on the carrier rods. This movement which, of course, must be synchronized with the operation of the three sets of carrier rod operating fingers already described, may be accomplished by the following mechanism.

Stops 104, 105 and 106 are connected to levers 116, 117 and 118 respectively. These levers are pivoted on a short shaft 119 attached to bracket 97 so that their rear ends which are provided

with rollers 120, 121 and 122 respectively, may engage with cams 123, 124 and 125 respectively. These cams are keyed to shaft 46 and they are designed so as to impart the necessary motion to the three operating levers to operate the stops as required. Similarly three operating levers 126, 127 and 128 pivoted at 129 are provided for stops 107, 108 and 109, the rear ends of which engage with three cams 130, 131 and 132, also keyed on shaft 46.

Whenever it is desired to restrict the movement of one of the carrier rods to the left the corresponding stop on stop block 103 will be pushed down into engaging position by means of one of the cams operating through one of the levers. Similarly when the motion of any one of the carrier rods to the right is to be reduced this is accomplished through the corresponding stop on stop block 102 which is pushed down into engaging position by the lever operated by the corresponding cam. The connection between the stops 104-109 and the levers just referred to is necessarily a sliding or otherwise flexible connection since the levers do not move longitudinally of the machine, whereas it must be possible to rack the stop blocks which carry the stops in and out in accordance with the requirements of the reinforcement. As a specific illustration of the operation of the machine assume the carrier rods to be in the position shown in Fig. 5 and position A-A of Fig. 2. The first stroke illustrated in position A of Fig. 2, it will be recalled, was from left to right and resulted in driving rod 23 the full width of the fabric. This would be done by finger 43 on friction 37 which would be permitted to engage with stop 59. Simultaneously rod 24 will be carried to the right across the right selvage by finger 81 which is permitted to engage with stop 94. Rod 25 will be moved simultaneously to the right across the left selvage by finger 66 on friction 38 which is permitted to engage stop 79. The inward travel of carrier rod 25 is arrested when stop 114 strikes stop 106 on stop block 102 which will occur when the thread carrier reaches the inner edge of the left selvage.

Upon the next stroke of the machine as shown in position B of Fig. 2 rod 23 is driven to the left the width of the right selvage. For this purpose finger 80 on friction 39 will be permitted to engage with stop 93. When the inner edge of the selvage is reached stop 111 will strike stop 107 on stop block 103 and the rod will come to rest. Simultaneously finger 44 on friction 37 has engaged with stop 60 on rod 24 and propelled it the full width of the fabric and finger 66 has engaged with stop 79 on rod 25 to drive it across the left selvage.

On the next stroke (position C of Fig. 2) carrier rod 23 is returned to the right across the right selvage by finger 80 on friction 39 which engages with stop 93. Carrier rod 24 is moved to the right across the left selvage by finger 65 acting upon stop 78, the motion being terminated at the inner edge of the left selvage by the engagement of stop 112 with stop 105 on stop block 102 and carrier rod 25 has been driven entirely across the fabric by finger 45 acting upon stop 61. Upon the next stroke (position D of Fig. 2) finger 43 will again drive rod 23 across the full width of the fabric by means of stop 59, finger 65 will drive rod 24 across the left selvage by means of stop 78, and finger 82 will drive rod 25 across the right selvage by means of stop 95, the travel of rod 25 being arrested at the inner edge of the selvage by the

engagement of stop 115 with stop 109 on stop block 103.

Upon the following stroke (position E of Fig. 2) rod 23 will be driven across the left selvage by finger 64 acting upon stop 77, its motion being arrested at the inner edge of the selvage by the engagement of stop 110 with stop 104 on stop block 102, rod 24 will be driven across the entire width of the fabric by finger 44 through stop 60 and rod 25 will be returned across the right selvage by finger 82 acting upon stop 95. The next stroke (position F of Fig. 2) will return the rods to their original position (positions A—A of Fig. 2) finger 64 engaging with stop 77 to propel rod 23, finger 81 engaging with stop 94 to propel rod 24, and finger 45 engaging with stop 61 to propel rod 25. Rod 24 is arrested at the inner edge of the right selvage by stop 113 which strikes stop 108 on stop block 103. From this it is evident that friction 37 acting through fingers 43, 44 and 45 and carrier rod stops 59, 60 and 61 controls the full width of travel of the carrier rods, that friction 38 acting through fingers 64, 65 and 66 and carrier stops 77, 78 and 79 controls outward movement (right to left) of the carrier rods working upon the left selvage; that this same friction through the same fingers and stops controls the movement of the same rods across the same selvage in the opposite direction within the limits permitted by stops 104, 105 and 106 on stop block 102 in conjunction with carrier rod stops 110, 112 and 114; that friction 39 acting through fingers 80, 81 and 82 and stops controls the movement of the carrier rods working from left to right upon the right selvage and that this same friction 39 acting through the same fingers and carrier rod stops controls the reverse movement of the rods across the same selvage to the extent permitted by stops 107, 108 and 109 on stop block 103 acting upon carrier rod stops 111, 113 and 115. It is also evident that the fifteen cams on changing shaft 46 can be made to operate the fingers and center stops to effect the movements described.

It will also be evident that the outer limits of carrier rod travel are defined by the standard end stops 40^a and 41^a so that the usual narrowing may be effected and that the width of the reenforced selvages may be determined and varied at will by racking stop blocks 102 and 103 inwardly or outwardly. It will also be evident that the operating sequence of the carrier rods may also be modified by altering the cams to correspond. In Fig. 5 a means for rotating changing shaft 46 is shown as consisting of a cam 133 upon the main cam shaft 134 operating a rock lever 135 through roller 136. Lever 135 in turn rotates shaft 46 in a step by step manner through a pawl 137 and ratchet 138. This form of drive is well known to those skilled in the art and can be designed by them to impart the required rotation to shaft 46 which will, of course, depend upon the design of the cams on shaft 46.

Fig. 5 also shows a similar drive for spindle 96. It consists of a cam 139 on main cam shaft 134, a rock lever 140 operated by cam 139 through roller 141, a pawl 142 on rock lever 140 and a ratchet 143 on spindle 96. This mechanism will cause stop blocks 102 and 103 to move inwardly in a step by step manner whenever required. This drive which, obviously, will not be used except when the inner edges of the selvages are to be moved inwardly may be thrown out of action by lifting pawl 142 out of engagement with ratchet 143 or in any other suitable way. To move stop blocks 102 and 103 outwardly the above mechanism may be

modified so that spindle 96 may be automatically rotated in either direction. Such a drive is well known to those skilled in the art and for that reason and to simplify the drawings a hand wheel 144 is shown by means of which blocks 102 and 103 may be racked out.

A clear idea of the construction of the fingers on frictions 37, 38 and 39 can be obtained from Fig. 6 which is an end view of friction 37 looking to the right from the position indicated by the line 6—6 in Fig. 5. It will be noted that to the rear end of each finger is attached a spring 145, the other end of which is attached to cross rod 55. Thus the fingers are maintained in contact with the carrier rod stops by these springs, the cams serving to elevate and maintain the fingers in inoperative position. Whenever it is desired to throw frictions 37, 38 and 39 out of action, this may be done by lever 146 by means of which a rod 147 carried by the friction box can be rotated. Rod 147 is provided with cams 148, one for each finger, which, when lever 146 is thrown back, engage with the fingers to elevate them into inoperative position and remove them from the influence of spring 145 and the several cams. This lever will be employed, for example, to throw all of the fingers on frictions 37, 38 and 39 out of operation when the point has been reached at which the knitting of the instep is suspended, as diagrammatically indicated at the lines B—B in Fig. 4. The completion of the heel tabs from that point is performed in the conventional manner by six carrier rods, three working on each tab to lay the three threads required for the doubly reenforced structure. Among these three rods two of the rods heretofore used would normally be employed to continue in the remainder of each heel tab one of the threads already incorporated in the upper part. This is perfectly feasible since all three rods 23, 24 and 25 have been disconnected from all of the fingers on all three frictions 37, 38 and 39. Therefore, for completing the heel tabs two of the rods, say 23 and 24, may be employed in conjunction with four other rods, not shown. All of them will be operated by ordinary frictions with which the standard friction rod is equipped through suitably placed stops on the carrier rods. These, of course, are also standard. This further emphasizes the fact that the device of this invention is one which in no way alters the other possibilities of the machine.

Fig. 7 shows in greater detail the construction of the modified pointed heel attachment, and particularly the stops and levers by means of which the inward travel of the carrier rods working on the selvages are controlled. Stop block 102 is shown and stop levers 104, 105 and 106 in their inoperative position into which they are moved and held by cams 123, 124 and 125 respectively, against the resistance of a spring 149 of which there is one for each lever. The upper end of each stop lever terminates in a slotted head 150 with the slot of which the proper lever 116, 117 and 118 slidably engages so that the stop levers remain operatively connected to the operating levers in spite of the inward and outward travel of block 102. In order that the correct relation between stop block 102 and cams 123, 124 and 125 may be positively maintained boss 103^a, which affords a sliding support on shaft 91, may also be extended into a half bearing 151 resting against changing shaft 46. This will positively maintain stop block 102 in its

proper position with respect to the operating cams and the carrier rods.

The structure of stop block 103, its stops 107, 108 and 109, associated operating levers, and operating cams 130, 131 and 132, is exactly the same as above described. The shapes of the cams shown in Fig. 7 are clearly illustrated. As already stated, the exact design will readily be determined by those skilled in the art and must be left to them since it depends upon various factors such as the rate of rotation of changing shaft 46 as compared with that of the main cam shaft, the number of teeth in the operating ratchet, etc.

15 I claim:

1. A flat knitting machine having a multiplicity of longitudinally reciprocable carrier rods, a multiplicity of means for reciprocating each of said rods, and selector means for enabling each 20 of said reciprocating means to engage with a single and different one of said carrier rods.

2. A flat knitting machine according to claim 1 in which the selector means is carried by a rotatable shaft.

25 3. A flat knitting machine according to claim 1 in which the selector means is slidably keyed to a rotatable shaft.

4. A flat knitting machine according to claim 1 in which the selector means consists of a multiplicity of cams rotatable in timed relation to the reciprocation of the carrier rods.

5. A flat knitting machine having a multiplicity of longitudinally reciprocable carrier rods, a friction rod provided with a multiplicity of means 35 for reciprocating each of said carrier rods, each of said reciprocating means consisting of a multiplicity of fingers, each engageable with a different one of said carrier rods, and selector means associated with each reciprocating means 40 for enabling a finger of each reciprocating means to engage with a single and different one of said carrier rods and for maintaining the other fingers of each reciprocating means out of engagement with the carrier rods.

45 6. A flat knitting machine according to claim 1 in which the selector means is operated from a timing mechanism.

7. A flat knitting machine having a multiplicity of longitudinally reciprocable carrier rods, a reciprocable friction rod provided with a multiplicity of means for reciprocating each of said rods, selector means for enabling each of said reciprocating means to drive a single and a different carrier rod at each traverse of the friction rod, mechanically operated means for arresting the traverse of any one of the carrier rods at a point intermediate its full traverse during the traverse of the friction rod, said means consisting of a stop block adjustable longitudinally of the carrier rods 50 and provided with stops selectively engageable with stops upon said carrier rods, and mechanically operated means for moving said stops on said stop block into and out of position to engage with the stops upon said carrier rods so that a stop on said stop block engages a stop on a different one of said carrier rods at each stroke of the friction rod.

8. A flat knitting machine having a multiplicity of longitudinally reciprocable carrier rods, a reciprocable friction rod provided with a multiplicity of means for reciprocating each of said rods, selector means for enabling each of said reciprocating means to drive a single and a different carrier rod at each traverse of the friction rod, mechanically operated means for arresting the

traverse of any one of the carrier rods at a point intermediate its full traverse during the traverse of the friction rod, said means consisting of a stop block adjustable longitudinally of the carrier rods and provided with stops selectively engageable with stops upon said carrier rods, and mechanically operated means for selecting the stop on said stop block which is to engage with a stop on a carrier rod to arrest the traverse of that carrier rod at the intermediate point.

5

9. A flat knitting machine having a multiplicity of longitudinally reciprocable carrier rods, a multiplicity of carrier rod driving means each engageable with a single carrier rod during each traverse of said carrier rods, means for engaging 15 a different one of said driving means with a different one of said carrier rods between each traverse of said rods, and mechanism for operating said engaging means in timed relation to the operation of means for arresting the traverse of 20 one of said carrier rods at a point intermediate its full traverse, said arresting means consisting of a pair of stop blocks each provided with a series of stops, one stop of each series being engageable with a stop on a different one of said carrier rods and a different stop of each series 25 being moved into engaging position in a predetermined sequence between successive traverses of the carrier rods.

10

10. A flat knitting machine having a multiplicity of carrier rods, a reciprocable friction rod, a multiplicity of frictions on said friction rod, carrier rod driving means on each friction engageable with each carrier rod, and selector means for enabling each of said driving means to engage 35 with a single and different one of said carrier rods.

11. A flat knitting machine having a multiplicity of longitudinally reciprocable carrier rods, a multiplicity of means for reciprocating each of 40 said rods, and selector means for enabling each of said reciprocating means to drive a different carrier rod at each successive traverse of the friction rod.

12. A flat knitting machine having a multiplicity of reciprocable carrier rods, a friction rod provided with a multiplicity of means for reciprocating each of said rods, selector means for enabling each of said reciprocating means to drive a different carrier rod at each traverse of 50 the friction rod, and mechanically-operated means for arresting the traverse at any one of the carrier rods intermediate its full traverse during the traverse of the friction rod.

13. A flat knitting machine having a multiplicity of longitudinally reciprocable carrier rods, a reciprocable friction rod provided with a multiplicity of means for reciprocating each of said rods, selector means for enabling each of said reciprocating means to drive a single and different 60 carrier rod at each traverse of the friction rod, means for arresting the traverse of any one of the carrier rods intermediate its full traverse during the traverse of the friction rod, said means consisting of a stop block adjustable longitudinally of the carrier rods and provided with stops selectively engageable with stops upon said carrier rods.

55

14. A flat knitting machine having a multiplicity of longitudinally reciprocable carrier rods, 70 each provided with a thread carrier, a friction rod provided with a multiplicity of means for reciprocating each of said carrier rods, selector means for enabling each of said reciprocating means to drive a single and different carrier rod 75

5 at each traverse of the friction rod, means for arresting the traverse of a predetermined one of the carrier rods when its carrier has reached the inner edge of the selvage, and mechanically-operated means for operating said arresting means in timed relation to the operation of the selector means.

10 15. A flat knitting machine having a multiplicity of longitudinally reciprocable carrier rods each provided with a thread carrier, a friction rod provided with a multiplicity of means for reciprocating each of said carrier rods, selector means for enabling each of said reciprocating means to drive a single and different carrier rod at each

traverse of the friction rod, means for arresting the traverse of a predetermined one of the carrier rods when its carrier has reached the inner edge of the selvage, said arresting means consisting of a stop block adjustable longitudinally of the 5 carrier rods and provided with stops each selectively engageable with stops on a different one of said carrier rods, and mechanically-operated means for engaging one of said stops on each said stop block with the stop upon the predetermined 10 carrier rod when the thread carrier upon said predetermined carrier rod has reached the inner edge of the selvage.

ALBERT FRIEDMANN.
